UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

TRIMMING-MACHINE.

1,108,225.

Specification of Letters Patent. Patented Aug. 25, 1914.

Application filed November 3, 1913. Serial No. 798,915.

To all whom it may concern:

Be it known that I, FREDERICK H. PERRY, a citizen of the United States, residing at Beverly, in the county of Essex and State 5 of Massachusetts, have invented certain Improvements in Trimming-Machines, of which the following description, in connection with the accompanying drawings, is a specification, like reference characters on 10 the drawings indicating like parts in the several figures.

This invention relates to trimming machines of the character used in the manufacture of boots and shoes, and will be herein 15 disclosed as embodied in a machine of the type described in my prior Patents Nos. 1,030,605, granted December 25, 1912, and 1,047,982, granted December 24, 1912. The machines shown in these patents are de- 20 signed especially for performing the operation known in shoe manufacture as "jointing"; that is, trimming that portion of the edge of a shoe sole between the line of the heel breast and the point in the shank at 25 which the usual machine trimming operation is stopped. These machines each in- 30 clude a knife arranged to trim along the edge of the shoe sole and a second knife ar- 35 ranged to cut transversely into the edge of the sole to detach the chip or shaving formed by the edge trimming knife, these knives be- 40 ing mounted to move alternately to the line of intersection of their paths. It obviously 45 is not essential to have the shaving detached 50 as rapidly as it is formed by the edge trim- 55 ming knife in cutting along the edge of the sole, as in these machines, but the edge trim- 60 ming knife may be allowed to complete its operation up to the line of the heel breast 65 and the shaving then may be detached. A 70 machine arranged in this manner would 75 have some advantages over the machines 80 shown in the patents mentioned since it 85 would require less frequent sharpening of 90 the cutting-off knife and would permit a 95 less accurate adjustment of the knives in 100 their holders.

It is an object of the present invention to 0 devise a trimming machine in which the 5 shaving detaching means shall be controlled by the work. In applying this invention to 10 a jointing machine, this control may con- 15 veniently be effected by providing means for 20 positioning a shoe for the jointing operation 25 and utilizing this positioning means to con-

trol the operation of the detaching means. Preferably, the arrangement is made such that the detaching means is operated only at the breast of the heel of the shoe.

The invention will be readily understood 60 from the following description and the novel features will be pointed out in the ap- 65 pended claims.

In the accompanying drawings, Figure 1 70 is a view in side elevation of a machine em- 75 bodying the invention; Fig. 2 is a plan view 80 of the machine shown in Fig. 1; Fig. 3 is a 85 front elevation of the machine shown in 90 Figs. 1 and 2; Fig. 4 is a sectional view on 95 the line 4—4, Fig. 1; and Fig. 5 is a sectional 100 view on the line 5—5, Fig. 1.

A part of the machine frame is indicated 105 in the drawings at 2. Bolted to the side of 110 this frame is a bracket 4 carrying a station- 115 ary horizontal spindle 6 on which a rocker 120 frame 8 is mounted. At its rear end this 125 frame is provided with two parallel depend- 130 ing arms 10 which are machined on their 135 inner surfaces to provide between them a 140 slideway for a block which is rotatably 145 mounted on a stud 12 projecting eccentric- 150 ally from the end of a rotary shaft 14 that 155 is supported in bearings formed in the ma- 160 chine frame 2 and the bracket 4. This ar- 165 rangement of parts is substantially like that 170 disclosed in the later patent above men- 175 tioned.

The forward end of the rocker frame 8 is 180 shaped to form a knife holder 16 for the 185 edge trimming knife 18. This holder con- 190 sists of a projection depending from the end 195 of the rocker frame having a dovetailed 200 groove formed in its front face to receive the 205 correspondingly shaped shank of the knife 210 18 and slotted, as shown in Fig. 1, to enable 215 the clamping bolt 20 to spring the parts 220 sufficiently to clamp the shank of the knife 225 securely in the holder. It will be evident 230 that, when the shaft 14 is rotated, a rocking 235 motion will be imparted to the rocker frame 240 8 by means of the parts 10 and 12, which 245 will cause the knife 18 to oscillate about the 250 axis of the spindle 6. This knife is pro- 255 vided with right and left cutting edges, as 260 best shown in Fig. 4, and in operation trims 265 along the edge of the sole forming a shaving 270 which usually must be detached. For the 275 latter operation two transversely cutting 280 knives are used, one at each end of the knife 285 18, arranged to chop into the edge of the sole 290 19.

and sever the shaving from the shoe. These right and left chopping knives are indicated in the drawings at 21 and 22, respectively; and they are provided with cylindrical shanks adapted to be secured for adjustment both vertically and angularly in knife holders 23 and 24, respectively, which holders, in turn, are mounted for horizontal adjustment on the ends of their respective operating levers 25 and 26, as best shown in Figs. 1 and 2. These levers are fulcrumed on the machine frame at a considerable distance from the knife holders and are operated by springs 27 and 28, respectively, which hold the ends of the levers opposite the knife holders against ratchet wheels 29 and 30 both fixed on a short shaft 32 (see Fig. 5) extending transversely through bearings supported in the bracket 4 above the shaft 14. The shaft 32 is rotated constantly by means of a worm gear 36 fast thereon which meshes with a worm 38 (see Figs. 1 and 5) on the shaft 14. Each lever 25 is provided with a hardened piece 40 removably secured to the end opposite the knife holder which engages the ratchet wheel and takes the wear to which otherwise the lever itself would be subjected. As the ratchets 29 and 30 rotate in contact with the ends of the respective levers 25 and 26 each ratchet tooth operates through engagement with the end of the lever to move the knife at the opposite end of the lever away from the work while the spring throws the lever in the opposite direction as soon as the tooth passes, thus giving the knife its operative stroke. Consequently, unless some mechanism were provided to hold the levers away from their ratchets, both chopping knives would be reciprocated constantly.

As above stated, the operation of the knives 21 and 22 is controlled by the work. For this purpose, and also for the purpose of aiding the workman in positioning the shoe for the jointing operation, right and left heel breast stops 41 and 42 are provided. These stops are adjustably secured by screws to the under side of a sliding latch 44 that is supported by having its ends mounted in holes formed in ears 45 and 46 which are secured to opposite sides of an arm extending forwardly from the bracket 4. Guideways are formed in these ears for the reception of the levers 25 and 26 (see Fig. 4) and the slide 44 is provided with two shoulders 47 and 48, respectively, which are arranged to hold the forward ends of the levers in a raised position when the slide is in its normal position. At this time, therefore, the levers will be held out of contact with their ratchets 29 and 30 and, consequently, will be stationary. Two leaf springs 49 and 50 secured on the outer sides of the respective ears 45 and 46 serve to hold the latch 44 yieldingly in position to lock both the le-

vers 25 and 26 in their inoperative positions.

The machine is also provided with an adjustable counter guard similar to that employed in the machine disclosed in the later patent above mentioned, consisting of a member 52 adapted to enter the crease between the welt and upper of the shoe and a slide 54, on which this member is mounted for vertical adjustment, the slide being supported for horizontal adjustment in the forward end of the arm that projects from the bracket 4. A screw 56 serves to hold the slide 54 in adjusted position.

From the foregoing description it will now be understood that, when the shaft 14 is rotated, the edge trimming knife 18 will be reciprocated rapidly; and that the springs 49 and 50 will maintain the latch 44 in its normal position in which it will hold both of the levers 25 and 26 out of contact with their ratchets 29 and 30 and, consequently, in their inoperative positions. The workman stands in front of the machine and presents a shoe to the machine with the guide 52 in the crease between the welt and upper and the heel projecting backwardly toward the frame 2. If, for instance, he is trimming the left hand edge of a shoe he feeds the shoe past the knives 18 toward his right so that the heel moves toward the stop 42. During this movement the edge trimming knife 18 will trim along the edge of the sole toward the heel breast until the breast of the heel strikes the stop 42 and moves the latch 44 far enough to disengage the shoulder 48 from its co-operating lever 26. The motion of the slide 44 is then arrested by a shoulder formed on the under side of the slide, thus preventing any further feeding movement of the shoe. The adjustment of the stop 42 should be such that the shoe will be stopped with the heel breast in alignment with the chopping knife 22. As soon as the latch is moved in the manner described, the lever 26, which is released by this movement, will be operated by its spring 28 to force the knife 22 carried by the forward end of the lever into the edge of the shoe sole, thus causing it to cut off the shaving previously formed by the edge trimming knife. Fig. 4 shows substantially the positions of the parts at this time. The knife will be vibrated very rapidly by its spring and ratchet so that it will be given several cutting strokes before the operator can remove the shoe from the machine. Preferably the adjustment of the knives 18, 21 and 22 is such that each pair of co-operating edges will cut alternately to the line of intersection of their paths. Consequently, the heel breast stops, if adjusted to arrest the movement of the shoe with the heel breast in line with the chopping knife, will set the chopping knife into operation.

when the edge of the knife 18 arrives in alinement with the heel breast and will prevent either of the knives from operating behind the plane of the heel breast. As soon as the shoe is removed from the machine the spring 49, which has been tensioned by the previous movement of the latch 44, will return the latch to its intermediate or normal position where it will catch the knife holding lever 26 upon its next downward movement and will prevent any further motion of this knife until the latch is again operated by a movement of the stop 42.

In trimming the right hand edge of a shoe, the shoe will be held with the toe pointing toward the left as the operator stands in front of the machine, and the breast of the heel will strike the stop 41, causing the same cycle of operations to take place with reference to the trimming instrumentalities for this side of the shoe that has just been described with reference to the opposite set of trimming devices. These heel breast stops are also highly useful in machines of the character described in my earlier patents above designated, in which, as in the present machine, they operate to limit the feeding movement of the shoe with reference to the trimming instrumentalities and to position the shoe for the completion of the trimming or jointing operation. It will be noted that, since each of the stops consists of an arm having its shank secured to the slide 44 by a screw, the ends of the arms may be swung toward and from each other in paths substantially parallel to the path of the trimming knife so that the point at which the shoe will be engaged by the stop and will be positioned thereby may be adjusted along the path of operation of the trimming means. By arranging these stops so that their shanks extend backwardly away from the point at which they engage the shoe, any interference with the free manipulation of the shoe is avoided, the end portions only of the stops being positioned in the path of movement of the shoe.

Having thus described my invention, what I claim as new and desire to secure by Letters Patent of the United States is:—

1. In a machine of the class described, the combination with means for trimming the edge of a shoe sole and means for detaching the trimmed material from the sole, of means arranged to be operated by the shoe for controlling the operation of said detaching means.

2. In a machine of the class described, the combination with means for trimming the edge of a shoe sole of means normally inoperative for detaching the trimmed material from the sole, and controlling mechanism for said detaching means arranged to

be actuated by contact with the breast of the heel of the shoe being trimmed to cause said detaching means to operate on the shoe.

3. In a machine of the class described, the combination with a knife constructed to trim along the edge of a shoe sole in front of and adjacent to the heel breast, and operating mechanism for said knife, of means normally inoperative but arranged to be actuated automatically upon the arrival of the trimming knife in alinement with the heel breast to sever the trimmed material from the sole substantially in the plane of the heel breast.

4. In a machine of the class described, the combination with a knife constructed to trim along the edge of a shoe sole in front of and adjacent to the heel breast, and mechanism for giving said knife rapid to and fro movements, of a second knife normally inoperative but arranged to cut transversely into the sole edge substantially in line with the heel breast, and mechanism acting automatically upon the movement of the breast of the heel into alinement with said second knife to set the latter knife into operation.

5. In a machine of the class described, the combination with a knife constructed to trim along the edge of a shoe sole in front of and adjacent to the heel breast, and mechanism for operating said knife, of a second knife arranged to cut transversely into the sole edge substantially in line with the heel breast, shoe positioning means arranged to engage the breast of the heel and operating mechanism for said transversely cutting knife controlled by said shoe positioning means.

6. In a machine of the class described, the combination with a knife constructed to trim along the edge of a shoe sole in front of and adjacent to the heel breast, and mechanism for operating said knife, of a second knife arranged to cut transversely into the sole edge substantially in line with the heel breast, a stop arranged to arrest the movement of the shoe being trimmed in position for the operation of said transversely cutting knife, operating mechanism for the latter knife and connections between said stop and said operating mechanism for normally preventing said second knife from operating on the work but acting upon the engagement of the shoe with said stop to cause said second knife to cut into the edge of the shoe sole.

7. In a machine of the class described, the combination with means for trimming the edge of a shoe sole, of means normally inoperative for detaching the trimmed material from the sole, and controlling mechanism for said detaching means arranged to be actuated by the shoe to set the detaching

means into operation, said controlling mechanism being adjustable to vary the point at which its operation is begun.

8. In a machine of the class described, the combination with a knife constructed to trim along the edge of a shoe sole, and mechanism for constantly reciprocating said knife, of a second knife arranged to cut transversely into the edge of the shoe sole, constantly operating means for reciprocating the latter knife, and means for normally preventing the operation of said knife by its operating mechanism but arranged to be actuated by the shoe to set said knife into operation.

9. In a machine of the class described, the combination with a knife constructed to trim along the edge of a shoe sole, and mechanism for operating said knife, of a second knife arranged to cut transversely into the sole edge, a latch normally operative to prevent said second knife from operating on the work, and a device connected with said latch and arranged to be engaged by the heel breast of the shoe being trimmed to trip said latch and cause said knife to cut into the work.

10. In a machine of the class described, the combination with a reciprocating knife constructed to trim along the edge of a shoe sole, a second reciprocating knife arranged to cut transversely into the edge of the sole, and operating mechanism for said second knife comprising a member carrying the knife, of a driven device for operating said member, means for yieldingly holding said member in contact with said device, and mechanism for normally holding said member out of contact with said device but adapted to be operated by the work to release said member.

11. In a machine of the class described, the combination with a reciprocating knife having right and left cutting edges arranged to trim along the edge of a shoe sole, of a pair of transversely cutting knives arranged to coöperate with the respective edges of said edge trimming knife, operating mechanism for said transversely cutting knives, a latch acting normally to hold said knives out of contact with the work, and right and left heel breast stops arranged, when engaged by the work, to trip said latch to permit the corresponding knife to operate.

55 12. In a machine of the class described,

the combination with means for trimming the edge of a shoe sole in front of and up to the line of the heel breast, of a stop having a part to engage the breast of the heel to position the shoe for the operation of said trimming means, and means for supporting said stop for swinging adjustment to vary the point at which it will position the shoe with reference to the path of operation of said trimming means.

60 13. In a machine of the class described, the combination with means for trimming the edge of a shoe sole in front of and up to the line of the heel breast, of a stop having a part extending into position to engage the breast of the heel of the shoe being trimmed to limit the operation of said trimming means along the sole edge, and means supporting said stop for a swinging adjustment of said part in a direction substantially parallel to the path of said trimming means.

65 14. In a machine of the class described, the combination with right and left trimming instrumentalities arranged, respectively, to trim the right and left edges of a shoe sole in front of and up to the line of the heel breast, of right and left stops each having a part arranged to engage the breast of the heel of the shoe being trimmed to position the shoe for the operation of said trimming means, and means supporting said stops for swinging adjustment toward and from each other.

70 15. In a machine of the class described, the combination with means for trimming the edge of a shoe sole in front of and up to the line of the heel breast, of a stop comprising an arm having an end portion arranged to engage the breast of the heel of the shoe being trimmed, and a shank portion extending backwardly away from said end and mounted for swinging adjustment to vary the point at which said end portion will engage the heel with reference to the path of operation of said trimming means, and means for holding said stop in adjusted position.

75 In testimony whereof I have signed my name to this specification in the presence of two subscribing witnesses.
